SEWING MACHINE

Frank Squarcia, North Plainfield, N. J.

Application August 10, 1939, Serial No. 289,343

17 Claims. (Cl. 112—38)

This invention relates to sewing machines, and is more particularly directed toward sewing machines of the type using waxed or glued threads such as employed in sewing soles on shoes.

Shoe machines of this general type employ two threads, one a machine thread operated by the needle and drawn through a wax container so that waxed thread is applied to the lower side of the work, and the second a waxed bobbin thread which is applied to the top of the work. In the ordinary procedure the operator passes raw thread from a large spool through a heated wax pot and winds it onto a comparatively small metal bobbin. This bobbin is inserted into a rotary shuttle which is kept hot during the operation of the machine. The amount of thread which can be stored on one of these bobbins is very small, and hence the amount of work which an operator can do with the machine without stopping to replace, reheat and perhaps rewind bobbins is therefore limited. This frequent replacement of bobbins with time consumed in heating them so that they can be used is a considerable handicap to the output of the operator.

The present invention contemplates a sewing machine having provisions to receive a regular spool of raw thread which is passed through a heated wax container and to the work. The receiver or support for the spool of raw thread and the wax container are constructed to form a unitary reciprocable shuttle which is passed back and forth by a sewing position, while other mechanism operated in timed relation to the shuttle operates the needle, picks up the machine thread from the needle, passes it above the shuttle whereupon it is released and passed down by the other end of the shuttle, so that it can be drawn into the work by the usual tightening mechanism.

A further object of the invention is to provide a heated guide along which the shuttle is caused to reciprocate so that the wax container and bobbin thread can be kept hot.

A further object of the invention is to provide a novel arrangement of shuttle comprising the spool support, the wax container and suitable guides for passing the bobbin thread from the spool through the wax container, and suitable tensioning and guiding mechanism so that it will be properly delivered to the work, and to arrange these parts so that a new spool of thread can be readily inserted and threaded through the wax container.

A further object of the present invention is to provide means for positively controlling the position of the shuttle at all times and yet permit

the loop of machine thread to pass down by the driven end of the shuttle.

Other and further objects of the invention will appear as the description proceeds.

The accompanying drawings show, for purposes of illustrating the present invention, one of the many embodiments in which the invention may take form, it being understood that the drawings are illustrative of the invention rather than limiting the same.

10

In these drawings:

Figure 1 is a front elevational view taken in the direction of the arrow 1 of Figure 3 with parts broken away and parts in section, and showing the shuttle and operating parts in the left hand position just before the needle thread has been lifted;

Figure 2 is a view similar to Figure 1 with the shuttle in the right hand position where it has passed through the loop of the needle or machine thread and the latter has been released;

Figure 2a is a fragmentary view taken from the rear showing the parts in the same position as Figure 2;

Figure 2b is a fragmentary diagrammatic view with the parts in the position of Figure 2 showing the path of the released machine thread;

Figure 3 is an elevational view taken from the left of Figures 1 and 2 and showing the rear end of the shuttle and its operating mechanism;

30

Figure 4 is an elevation view with parts in section and taken from the right of Figures 1 and 2;

Figure 5 is an enlarged sectional view taken on the line 5—5 of Figures 4 and 10 showing the spool holder, the thread guides and the wax container, the latter being in the lowered position;

35

Figure 6 is a view taken in the direction of the arrow 6 of Figure 5 showing the spool holder and certain of the thread guides;

Figure 7 is an elevational view taken from the left of Figure 5 as indicated by the arrow 7;

Figure 8 is an inverted plan view of the shuttle;

Figure 9 is a fragmentary sectional view on the line 9—9 of Figures 2 and 5;

Figure 10 is a fragmentary sectional view on the line 10—10 of Figure 5;

45

Figure 11 is a diagrammatic view illustrating the thread guides of the shuttle; and

Figure 12 is a diagrammatic view illustrating the timing relation of the mechanisms employed.

50

The usual horizontal power shaft of the sewing machine is indicated at 10 and fixed brackets are indicated at 11, Figure 3, and at 12, Figure 4. These brackets support an obliquely extending back plate 13 and a front plate 14 generally

55

parallel therewith and secured to it by means of bolts 15. The brackets 11 and 12 also support an obliquely disposed longitudinally extending bar 16 with a T-shaped lower edge, as indicated at 17.

5 A suitable cam, not shown, but mounted on the shaft 10 actuates a rocker arm 18 back and forth with a suitable rest period at each end of the stroke. The end of the arm is bifurcated, as indicated at 19, to receive a pin 20 secured to a slide 21 guided in vertical grooves 22 in the plates 13 and 14. This slide is connected by a short link 23 to the short arm 24 of a bell crank pivoted at 25. The lower end 26 of the bell crank is bifurcated 10 and has arms 26a and 26b spanning the guide bar 16, and having elongated slots 27 to receive rollers 28 mounted on a shaft 28' carried by shuttle 15 actuating slider 29. This slider is guided for reciprocation along the bar 16, as will be obvious 20 from Figures 1 and 2.

The slider 29 carries a transversely extending shaft 30 which passes through a recess 31 opening toward the right, as will be apparent from Figure 9. The shaft 30 fixedly carries two annular members 32 and 33 disposed in the recess 31 each having inwardly facing annular flanges 34 and transversely extending notches 35. The rear end of the shaft 30 is squared, as indicated at 36, Figure 2a. At the left of the machine is a downwardly 25 extending arm 37 having a slot 38 to receive a bar 39. A leaf spring 40 urges the left end of the bar upwardly. The other end of the bar slopes as indicated at 39', is provided with a leaf spring 41 bearing on an abutment 42 so as to support the bar 39, and with a slot 43 for a pin 44. The squared end 36 on the end of the shaft 30 and the bar 39 cooperate to assure that the parts carried by the shaft 30 will be turned a quarter of a revolution when the machine thread is tightened. 35

40 This will be described below.

The slider 29, through the medium of the toothed rotary members 32 and 33, is coupled with a shuttle designated generally by S and shown in detail in Figures 5 to 11, inclusive. As 45 here shown the shuttle comprises a spool holder 50 and a wax container 51. The shuttle has a T-slot 52 to ride along the grooved lower edge 17 of the guide 16. The wax container also has a T-shaped slot 53 so that it can similarly ride along 50 the groove 17. The spool container 50 has arcuate grooves 54 which receive the segments of the rotary members 32 and 33 and extend far enough so that one segment will enter the groove before 55 the other segment has passed from it. Hence the shuttle is always connected to its reciprocating means.

The spool container 50, as shown in Figure 5, has a chamber 55 adapted to receive a commercial spool of raw sewing thread, as indicated at 56. 60 This spool of thread is received on a flanged tube 57 which in turn is supported on a shaft or spindle 58 secured at its inner end to the container. The lower right hand corner of the container 50 is provided with a transversely extending hinge pin 59 on which is secured a bridging member 60 which is adapted to be swung down to the position shown in Figure 5 to permit inserting the spool, or swung up to the position of Figures 1 and 6 to support the spool and provide thread guides. It has a bearing hole 61 to fit over the end of the shaft 58. 65 It is slotted as indicated at 62 and 63 and a pin 64 extends across these slots.

70 Two arms 65 and 66 are pivoted to the left end of the spool holder, as indicated at 67, and support the wax container 51 so that it can be moved

from the position of Figures 1 and 2 down to the position of Figure 5. The wax container is of generally triangular shape in horizontal cross section, as will appear from Figure 8, and has a tapered or V-shaped front end 51' to facilitate spreading the loop of machine thread as will be described. The rear wall of the wax container is indicated at 68.

5 A bell crank shaped lever 69 is pivoted on a shaft 70 and urged in a counterclockwise manner 10 by a spring 71. The upper arm of this bell crank member bears against the lower surface of the bar 16 when the wax container is in the upper position, as shown in Figure 1, and acts to conduct heat from this bar down into the wax container, 15 the bar being heated by electric heaters diagrammatically illustrated at 72.

In order to releasably lock the wax container in the upper position, a portion of the bar 16 is cut away, as indicated at 73, and a plunger 74 is provided to release the wax container when the shuttle has been brought to the proper position. This position is indicated in Figure 5. The plunger may be actuated to releasing position by 20 a bell crank 75, Figure 4.

25 The path of the shuttle or bobbin thread B from the spool is indicated in Figure 11. It first passes through the slot 63 and over the shaft 64, then down over the shaft 70. It then passes about a guide 76 carried on the lower end of the bell crank 30 69, and then up past the shaft 70 and a spring 35 pressed tensioning device, indicated at 77, Figure 10. It then passes through the slot 62 and over the pin 64 and down through the space behind the wax container and an opening 78 in the bridging member 60 adjacent the hinge pin 59.

The lower side of the spool container is provided with two longitudinally extending guide rods 79 and 80 on which is secured a thread tightening slider 81. Coiled springs indicated at 82 and 83 40 urge the thread tightener to the left. The slider 81 carries a pin 84 over which the thread passes, as indicated in Figure 11. The thread is then down in the proper position to cooperate with the machine or needle thread M. The slider is pulled 45 from the position of Figure 2 to the position of Figure 1 when the shuttle is shifted to the left.

The sewing needle and awl of usual construction and operated by the usual mechanism are indicated at 90 and 91, respectively. They 50 co-operate with the work on the work support in the usual manner. The machine thread M comes up through the wax pot, not shown, and is picked up by the needle in the usual way and a loop pulled up through the work. The loop is spread by the 55 usual finger 92 as indicated in dot and dash lines in Figure 4, and is then picked up by a pair of reciprocating fingers indicated at 93 and 94. The upward movement of the fingers 93 and 94 is accomplished by a cam-actuated rocker arm 97, 60 Figures 1 and 2, which operates a slider 98 riding in grooves 99 in plates 13 and 14. The slider 98 is connected by a link 100 with an arm 101 pivoted at 101' which actuates the fingers. The path of the fingers is controlled by fixed cams 102 through 65 which rollers 103 pass.

The fingers 93 and 94 move the machine thread along the path indicated by the heavy dotted line 95, Figure 1, to carry the loop up 70 above the shuttle at which time the loop extends across a notch 96 formed in the guide 16 in a position to be pushed off the fingers by the projection 106 on the slider 29. When this occurs the usual thread tightener comes into action 75 and pulls the bobbin thread down as indicated 75

in Figure 2b. It passes between the spool container and the slider 29 and enters into the slots between the teeth on the wheels 32 and 33 and turns these wheels a sufficient amount to permit the thread to free itself from them. This turn will be approximately a quarter revolution, and when the shuttle retreats from the position of Figure 2 to the position of Figure 1 the squared end 36 on the shaft 30 will ride along the portion 39' of the bar 39, and this will definitely position the shaft 30 so that the next pair of notches will be in position to receive the loop formed in making the next stitch. If for any reason the sliding of the squared head 36 along the bar 39 fails to turn the shaft 30 to the proper position, the corner of the squared head 36 will enter into one or the other of the notches 39" on the bar 39 insuring that the parts will be correctly positioned.

The cycle of operations is diagrammatically illustrated in Figure 12. Assuming that the start of the cycle is as indicated, the cams are arranged so that the awl punches the hole in the work and the shuttle retreats from the position of Figure 2 to the position of Figure 1 at the same time. The fingers 93 and 94 are then lowered. Next the needle operating mechanism, not shown, functions in the usual manner to lower and raise the needle. After the needle is raised and lowered the spreader 92 spreads the thread and the fingers 93 and 94 engage it and raise it above the path of the shuttle. The shuttle then advances and pushes the loop off the fingers whereupon the tightening mechanism acts to pull the bobbin thread into place and complete the stitch.

It is obvious that the invention may be embodied in many forms and constructions within the scope of the claims and I wish it to be understood that the particular form shown is but one of the many forms. Various modifications and changes being possible, I do not otherwise limit myself in any way with respect thereto.

What is claimed is:

1. A sewing machine having a shuttle including a casing open at one end and having a shaft adapted to receive a spool of raw bobbin thread from the open end of the casing and support the spool, a wax container disposed across the open end of the casing, guides for directing the thread through the wax container and delivering the waxed bobbin thread into a sewing position, means for heating the wax container, shuttle operating mechanism, and needle and looper mechanism acting on a machine thread to pass the same about the shuttle and form stitches in cooperation with the bobbin thread.

2. A sewing machine such as claimed in claim 1, wherein the shuttle is reciprocated along a heated guide from which heat is transferred to the wax container.

3. A sewing machine such as claimed in claim 1, wherein the wax container is movable to afford access to the spool storage means and for refilling of wax.

4. A sewing machine such as claimed in claim 1, wherein the shuttle operating mechanism has means for disengaging the thread from the looper mechanism.

5. In a sewing machine, a shuttle including a casing open at one end and having a shaft adapted to receive a spool of raw thread from the open end of the casing and support the spool, a wax container disposed across the open end of the casing, thread guides for directing

the thread from the spool through the wax container, a shuttle guide substantially parallel with the spool axis and to which the shuttle is slidably secured, and means to reciprocate the shuttle along the shuttle guide.

6. In a sewing machine, a shuttle including a casing open at one end and having a shaft adapted to receive a spool of raw thread from the open end of the casing and support the spool, a wax container disposed across the open end of the casing, thread guides for directing the thread from the spool through the wax container, a heated shuttle guide in thermal contact with the wax container and disposed substantially parallel with the spool axis and to which the shuttle is slidably secured, and means to reciprocate the shuttle along the shuttle guide.

7. In a sewing machine, a shuttle having a support adapted to hold a spool of thread, a shuttle guide substantially parallel with the spool axis and to which the shuttle is slidably secured, means to reciprocate the shuttle along the shuttle guide, means for lifting the machine thread from the usual needle to form a loop through which the front end of the shuttle may pass, and means for releasing the loop after the shuttle has passed through it and for providing a passage to the rear of the shuttle for the released loop before the shuttle returns without disconnecting the shuttle from its operating means.

8. A sewing machine such as claimed in claim 7, wherein the guide has an opening to receive said loop.

9. In a sewing machine, a shuttle having a support adapted to hold a spool of raw thread, a wax container, thread guides for directing the thread from the spool through the wax container, a shuttle guide substantially parallel with the spool axis and to which the shuttle is slidably secured, means to reciprocate the shuttle along the shuttle guide, movable fingers for lifting the machine thread from the usual needle to form a loop through which the shuttle may pass, means for effecting disengagement of the machine thread from said fingers, and means acting on said thread to pull it down past the rear end of the shuttle without disconnecting the shuttle from its operating means.

10. In a sewing machine, a shuttle having a support adapted to hold a spool of thread, a shuttle guide substantially parallel with the spool axis and to which the shuttle is slidably secured, a reciprocatory slider secured to the guide and disposed to the rear of the shuttle, means for reciprocating the slider, and a coupling between the slider and shuttle through which a loop of thread can be passed without separating the shuttle from the slider.

11. In a sewing machine, a straight guide, a shuttle slidably mounted on the guide, and having an arcuate element adjacent one end, a slider on the guide, and a toothed member rotatably carried by the slider and having arcuate elements engageable with the arcuate element on the shuttle and of less arcuate extent than the same to couple the shuttle and slider together while the toothed member is rotated.

12. In a sewing machine, a reciprocatory shuttle adapted to hold a spool of thread and having thread guides to deliver a bobbin thread for sewing, a supply of machine thread, a needle acting as the machine thread to pass a loop through the work, a device for spreading the loop and removing it from the needle, loop lifting devices, means to direct the lifting devices into the loop

to lift it upwardly past one end of the shuttle and spread the loop, while the shuttle is in one position, means to shift the shuttle through the loop and for then disengaging the loop from the 5 loop lifting devices, and means for drawing the loop down past the other end of the shuttle to tie in the bobbin thread.

13. In a sewing machine, a horizontal shuttle 10 guide bar, a shuttle reciprocably mounted therein, a shuttle operating slider having a driving connection therewith through which a thread loop may be passed, shuttle reciprocating means, a needle operating on a horizontal axis below the bar, a looper having a generally vertical movement for passing a loop of thread from the needle upwardly about the shuttle, and a loop tightener 15 for drawing the loop downwardly.

14. In a sewing machine, a spool holder having an open end adapted to receive a spool of raw 20 sewing thread and a spindle to support the spool, a normally heated, fixed supporting guide generally parallel with the spool axis and along which

the spool holder may be reciprocated, a wax container having a guiding connection with the fixed guide and secured to the spool holder for bodily movement therewith, a heat transfer shoe carried by the wax container for transferring heat to the wax, and thread guides for directing thread from the spool through the wax. 5

15. A sewing machine such as claimed in claim 14, wherein the wax container is opposite the open end of the spool holder and may be disconnected from the fixed guide, so that the wax container may be moved to expose said open end. 10

16. A sewing machine such as claimed in claim 14, wherein the thread guides include tensioning means. 15

17. A sewing machine such as claimed in claim 14, having additional thread guides for directing the thread downwardly between the spool holder and the wax container and a slack take-up device secured to the lower side of the spool holder. 20

FRANK SQUARCIA.
